PIPE MOLDING APPARATUS

Herbert H. Farr, Alexander City, Ala., assignor to
Ferro-Spun Corporation, a corporation of Ala-
bama

Application November 24, 1937, Serial No. 176,375

16 Claims. (Cl. 22—16)

This invention relates to mechanism for the centrifugal casting of pipe and like hollow bodies in a sand lined mold or flask.

The centrifugal casting in sand of pipe as at present practiced generally calls for the following sequence of steps, to-wit; the empty flask with its spigot end up and body and hub patterns centered has a sand lining rammed therein; the sand is then struck off at the spigot end of the flask, the body pattern is drawn, and the flask lifted to draw it from the hub pattern; the flask still in upright position is set on a pouring table and faced by the application of a carbonaceous coating composition to the walls of the sand mold; the flask is then laid horizontal on a bed and its sand lining is skin dried after which a hub sand core is mounted in place; the flask in its turn is then placed horizontally on a roll bed and spun or rotated rapidly while the molten metal is poured into its open spigot end; as soon as the molten metal becomes uniformly distributed about the mold and solidifies, the flask is removed from the roll bed, the sand and casting are shaken out, and the empty flask is returned to resume the cycle.

The speed and accuracy with which these various steps can be performed and coordinated obviously determines both the labor cost and the output of a pipe producing unit, and the objects of my present invention are so to design the flask and its related elements that many of these steps can be carried out with greater ease, speed and accuracy.

For instance, I propose to mount permanently in the flask a spigot strip plate which is apertured for the introduction of the sand into the flask during the ramming operation; I mount for rotation on such strip plate an apertured sand striking plate carrying the spigot flange pattern and serving as a stripping plate for the cylindrical body pattern; I replace the sand striking plate with a spigot plate and mount same in position to close the apertures in the spigot strip plate and also the spigot end of the mold except for a center pouring opening; I provide a removable hub strip plate adapted to overlap the marginal edge of the hub core while presenting only a corner edge to the metal forming the pipe hub so as to avoid chilling same; I provide the flask with annular end flanges recessed to receive their respective strip and pattern plates and their assembling bolts and only the strip plates and hub core plate are centered by these flanges, the other parts, such as the hub and spigot patterns, and the spigot plate being centered from the inner edges of the strip plates whereby I avoid any close fits for such removable parts in the end flanges; I use only one pair of bolts or fastening elements to mount each strip plate in its respective ring and I further secure it by a second pair

of bolts or fastening elements which mount the related spigot or hub core plate in the rings; I form a centering ring on the inner face of the spigot plate carrying a bevelled edge that forms a chill for the spigot end of the pipe and is made wide enough to accommodate pipes having different thicknesses of metal so that a given soil pipe whether of standard, medium, and extra heavy out grade can be cast against the same spigot plate; I form the hub core plate with a hollow body portion projecting into the hub core and apertured to vent the moisture from the hub core while it is being baked and to assist in venting the gases from the poured flask; and in a novel manner I mount the pouring spout so as to be guided into and out of the flask and to be readily demountable from its guides to facilitate its inspection, cleaning, and repairing.

My invention further comprises the novel details of construction and arrangements of parts which, in their preferred embodiment only, are hereinafter described and claimed, reference being had to the accompanying drawings in which:—

Fig. 1 is a plan view of a sand lined centrifugal pipe molding apparatus in accordance with my invention with the flask shown in position to be poured on a spinning bed.

Fig. 2 is a side elevation of Fig. 1, partly broken away in vertical central cross-section through the spigot end of the flask and through the pouring spout.

Fig. 3 is an enlarged detailed cross-sectional view of a portion of the spigot plate showing the relative size of its flared chill face with relation to the thickness of standard soil pipe, the dotted lines indicating the extra thickness of medium and extra heavy soil pipe.

Fig. 4 is a sectional view on an enlarged scale taken on the section line IV—IV of Fig. 1.

Fig. 5 is an exploded view in vertical cross-section, enlarged, of the spigot end of the rammed flask.

Fig. 6 is a half plan view of the spigot end of the flask with the spigot plate in position.

Fig. 7 is a similar view partly broken away showing the spigot plate removed to expose the spigot strip plate.

Fig. 8 is a view corresponding to Figs. 6 and 7 showing the spigot pattern plate in position in the pipe flask after the body portion has been drawn.

Fig. 9 is a vertical central cross-sectional view through the rammed flask showing the body, spigot and hub core patterns in place and the flask broken away.

Fig. 10 is a transverse cross-sectional view through hub end of the flask showing the hub strip plate, and the hub core and core plate, assembled in pouring position.

Fig. 11 is a half bottom view of the hub and of the assembled flask shown in Fig. 10.

Fig. 12 is a detailed view partly broken away of the hub strip plate.

5 Similar references hereinafter refer to similar parts throughout the drawings.

In the embodiment of my invention illustrated in the drawings I show conventionally a spinning bed frame 15 having roller bearing shafts 16 journaled in suitable bearings 17. One of the shafts carries a driving pulley 18 driven by suitable belting 19 from a pulley 20 fast on a drive shaft 21. The shafts 16 carry opposed pairs of grooved rollers 22 which receive the riding rings 15 23 on the cylindrical centrifugal pipe flask 24 which is adapted to have its rings 23 held in running position on the grooved rollers 22 by grooved hold-down rollers 25, each suitably mounted in a frame 26 which has offset pivotal 20 mounting by means of which each hold-down roller is adapted to be swung away from running position and permit the insertion and removal of the flask relative to the spinning frame.

It will be understood that the structural details 25 of the spinning frame and its hold-down rollers may be varied, those shown being of conventional design and suitable for illustrative purposes.

The flask is provided near its center with opposed side trunnions 27 and has a shake-out strap 30 28 attached thereto, all as described and claimed in my companion application Serial No. 176,376 for a Sand lined centrifugal pipe mold, executed concurrently herewith.

The flask 24 comprises a cylindrical tubular body perforated throughout for the free venting of moisture and gases therethrough, and at each end it is externally threaded to receive the threaded hubs of duplicate flanges indicated at 29 and 30 which form countersunk seats, the inner wall of which stands flush with the adjacent flask end. The circumferential marginal wall 31 of each flange is adapted to receive the related strip plate and pattern elements which will be hereinafter described.

45 Referring to Figures 5 to 7, the flange 29 at the spigot end of the flask is here shown with the spigot strip plate 32 permanently attached to the flange seat, in close marginal engagement against the flange wall 31, by means of two screws 50 33 whose heads are countersunk in the outer face of the strip plate. This strip plate has an annular series of apertures 34 which define an inner centering ring 35 and leave radial webs 36 connecting same to the plate proper. These apertures stand with their outer curved edges in register with the internal surface of the flask 24 and form openings through which sand can be freely introduced into the flask during the ramming operation.

60 After the flask has been rammed a spigot plate 37 is mounted in the flange seat 29 against the strip plate 32 by means of two bolts or like fastening elements 38 which pass loosely through registering holes 39 and 40 provided therefor in the strip plate 32 and the flange 29. It will be noted, however, that this spigot plate 37 does not fit closely against the marginal flange wall 31 but is centered by the shoulder 41 on its inside face which seats snugly within the stripping plate 70 centering ring 35. The thickness of this shoulder corresponds to that of the strip plate and the under face 42 of this shoulder is struck on an upward inward bevel and constitutes the chill against which the bevelled end of the pipe spigot 75 is to be cast.

It will be noted, by reference to Figure 3, that this face 42 is substantially wider than the spigot end 43 of the pipe casting which is shown of standard thickness, while the dotted lines indicate other thicknesses of the spigot end of the pipe casting for medium and extra heavy grades. From this it will be seen that pipes of a given size having all the thicknesses of different grades are adapted to be cast against the same spigot plate chill face 42. The spigot plate serves to close sand apertures 34 shown in the permanently attached spigot strip plate 32.

In Figs. 8 and 9, I illustrate a spigot pattern and sand striking plate that is set loosely in the flange 29 on the strip plate 32 during the ramming operation. This pattern plate comprises an annular flat body 45 which has an external diameter less than that of the flange face 31 so that it will fit loosely thereinto and can be turned freely therein. There is provided a series of apertures 46 in this plate 45 approximately corresponding in size and position to, and therefore adapted to register with, the apertures 34 in the strip plate 32, and it has an inner ring portion 47, corresponding to 35, which is elongated and shaped to form the pattern 48 for the spigot ring. This pattern 48 is cylindrical and is adapted to snugly fit in the centering ring 35 on the strip plate 32 so as to be centered thereby. Its internal diameter is such that it will receive and center the body pattern 49 which is a cylindrical element having its lower reduced end 50 adapted to be received in, and centered by, the open upper end of the hub pattern 51 that is bolted to a ramming table and serves also to center the flask 35 thereon by the engagement of the base of the pattern 51 with the central opening in the strip plate 53. The shoulder 52 on the pattern fits loosely in the hub flange 30.

I mount an opposed pair of outwardly bent handles 70 near the marginal edge of the spigot pattern plate 45 by means of which the same, while loosely seated on the spigot strip plate 32, may be rotated, after the ramming operation, to strike the sand at the top of the flask; after this the operator also by means of these handles holds this pattern plate 45 against the strip plate 32 while the body pattern is being drawn, after which this pattern plate 45 is drawn and is replaced by the spigot plate 37 already described.

Referring to Figs. 9, 10 and 12 I show an annular hub strip plate 53 mounted in the hub flange 30 with a snug fit against its face 31 by means of two bolts 54 having their heads countersunk in the under or outer face of the plate 53 and passing through the hub flange 30 to receive nuts which will demountably assemble it in said flange with its inside peripheral edge overhanging inwardly beyond the wall of the flask 24 to a position where it will coincide with the outer marginal corner edge of the hub when cast in said mold. As will be seen in Fig. 12 the outer marginal edge of the strip plate 53 is cut away to provide it with four opposed portions, the outer edges of which lie in a circle concentric with the center of the strip plate and in each of these four portions I provide a bolt hole, two opposite holes being countersunk to receive the bolts 54 and the other two holes being plain.

When the rammed flask is ready to be poured, I assemble in the hub flange 30 a hub core plate 55 whose outer marginal edge fits snugly within the marginal face 31 of the hub flange, and this plate is apertured to receive two bolts 56 which pass through the strip plate 53 and the hub flange 75

30 and receive nuts which secure this hub core plate in position.

The hub core plate is cast with an open center surrounded by an upwardly tapered, frusto-conical body portion 57 provided with side core vent holes and with a top opening 58 concentric with the flask and adapted to assist in venting gases from the latter during the pouring operation. This body portion 57 is provided with one or more 10 circumferential beads 59 which serve to anchor the hub sand core 60 thereon. This sand core is seated in an annular countersunk recess formed in the core plate 55 between the base of the body 57 and an annular shoulder 61 which is disposed 15 so as to be overhung by the inner peripheral edge of the hub strip plate 53. The base of the hub sand core is shaped to form a marginal flange 62, overhung by the hub strip plate, and a shoulder, 20 63 abutting and equal in height with the thickness of said strip plate. The sand lining 64 at the hub end of the flask rests against the strip plate 62 and defines with the core 60 the cavity for the formation of the pipe hub. As shown in Fig. 10, the hub strip plate is not disposed to form a chill 25 for the end of the pipe hub as its upper corner alone borders on the mold cavity without forming an appreciable part thereof.

Referring to Figs. 1 and 2 it will be noted that I provide a stand 65 at the pouring end of the 30 spinning frame 15 and mount thereon a slotted slide guide 66 for the pouring spout 67, the guide slot being in line with the vertical central plane through a flask when in pouring position on the spinning frame, and this slot is adapted to receive 35 a pair of aligned guide pins 68 depending from the bottom of the pouring spout. These pins may be in the form of bolts adapted to receive nuts, if it be desired to suitably connect the spout to the slide guide, but I prefer to leave the guide pins 40 plain so that the pouring spout can be readily lifted off from the frame for more convenient cleaning, inspection, and repairing. The pouring spout is lined with suitable refractory material indicated in 69 and is provided with a nozzle 71 almost circular in shape with a narrow top slot 72. This nozzle is also lined with a refractory 69 and is substantially coaxial with the flask and with the pouring hole at the center of the spigot plate 31 (see Fig. 4) into which it fits substantially 45 concentrically with a marginal clearance all around for the venting of gases from the flask during the pouring operation. I thus provide for venting the flask gases from both ends of the flask, but the vent opening at either end may be made large 50 enough for all practical purposes. Both vent holes are disposed above the molten metal level in the flask before the same is centrifugally distributed over the whole sand mold surface which is easily arranged in a soil pipe molding flask since 55 the volume of molten metal required for the casting is relatively small.

In Fig. 2 the finished casting 73 is shown in the sand mold after the pouring operation has been carried out on the spinning bed. To pour a pipe, 60 the flask is lowered onto the rolls 22 on the spinning bed with its riding rings 23 engaged in the groove of said rolls. The pivoted frames 26 are then rocked into the position to lower the hold-down rolls 25 into engagement with the top of the 65 riding rings. The pouring spout 67 is adjusted to the position shown in Fig. 2 and the requisite charge of molten metal, which has been weighed so as to introduce only the correct volume, is thereupon poured into the spout 67 and allowed 70 to flow freely through the nozzle 71 into the sand 75

mold within the flask. As the pouring operation is completed the drive is started up and the rolls 22 on the power driven shaft 16 start the rotation of the flask and bring it up to the requisite speed to effect a centrifugal distribution of the molten metal over the whole surface of the sand lined mold. The spinning operation continues until the casting solidifies, the gases meanwhile making their escape through either or both ends of the flask which are left open for that purpose. 10

When the pouring operation is completed, the hold-down rolls 25 are lifted and the flask is removed in any desired way from the spinning table to be replaced by the next flask to be poured. The arrangement of the hold-down rolls is illustrative merely as any convenient or practical means may hold the flasks in driving relation with the rolls 22, which is all that is necessary, provided such means will conveniently permit of the introduction and removal of the flask from 15 the spinning table. 20

The apparatus is designed to utilize a relatively thin sand lining in the flask, such as can be readily dried during the short interval of time required in continuous casting practice, for 25 a rammed flask to advance from the lining station to the spinning table.

It is to be noted that the permanently attached spigot strip plate 32 serves as the means for centering all of the other elements associated 30 with the spigot end of the flask from their center outwardly, thus avoiding the necessity of a close fit between these interchangeable elements and the flask flange 29. At the hub end the hub strip plate 53 and pattern plate 55 are the 35 only removable elements that are required to fit snugly into pipe flange 30 to be centered thereby, and when they are bolted together the plate, by its overhang, effectively clamps the hub sand core by its flange 62 and holds it down, 40 and by the engagement of its inner peripheral edge with the sand core shoulder 63 it affords an accurate centering for the sand core. 45

While I have shown my invention in but one form, it will be obvious to those skilled in the 45 art that it is not so limited, but is susceptible of various changes and modifications, without departing from the spirit thereof, and I desire, therefore, that only such limitations shall be placed thereupon as are imposed by the prior 50 art or as are specifically set forth in the appended claims.

What I claim is:—

1. A pipe flask for centrifugal sand molds having at its spigot end an annular strip plate 55 mounted in position to define the spigot end of the sand mold and apertured to provide for the admission of sand to the flask during the ramming operation, a striking plate rotatably and demountably seated above said strip plate 60 in position to strike off excess sand left above the latter after completion of the ramming operation, said striking plate being also apertured so as to register with the apertured strip plate, and means for rotating said striking plate to 65 strike off said excess sand.

2. A pipe flask for sand molds having at its spigot end a flange, an annular strip plate attached to said flange and disposed across the spigot end of the flask in position to define the 70 spigot end of the sand mold, said plate being apertured to provide for the admission of sand to the flask, an annular striking plate demountably seated on said strip plate and having sand apertures adapted to register with the apertures 75

in said strip plate and having at its inner periphery a spigot flange pattern forming an annular bearing adapted to be rotatably engaged within the strip plate, and means to rotate said striking plate to strike off the rammed sand above said strip plate.

3. A pipe flask according to claim 2, in which the sand striking plate is centered by the engagement of its said pattern with said strip plate and is adapted to act as a strip plate for a body pattern.

4. A flask for sand molds having at its spigot end a flange forming an annular seat, an annular spigot strip plate mounted in said seat in position to define the spigot end of the sand mold and apertured for the admission of sand to the flask, a sand striking plate, apertured for the passage of sand, which is detachably mounted on said strip plate and has depending from its center a spigot flange pattern adapted to engage in, and be centered by, said strip plate, handles on said demountable plate for rotating it and holding it in place, and a body pattern adapted to be inserted through and centered by said flange pattern and also to be stripped thereby when it is drawn from the flask.

5. A flask having an annular spigot strip plate permanently attached thereto and apertured for the admission of sand into the flask, and a spigot plate demountably attached over said strip plate to close the sand apertures and having a central pouring hole surrounded by an annular flange interfitting with said strip plate and bevelled to form the chill for the end of the pipe spigot.

6. A flask according to claim 5, in which said bevelled chill face on the spigot plate is made wide enough for use with pipes varying in thickness of metal at their spigot end.

7. A flask according to claim 5, in which the spigot plate is centered by means of the engagement of its center flange with an inner peripheral edge of the strip plate.

8. A pipe flask having a strip plate bolted to its spigot end and apertured for the passage of sand therethrough, an annular spigot plate detachably mounted on said strip plate in position to close the apertures therein, and a chill mold ring on said spigot plate adapted to seat in the center of the spigot plate with its inner face bevelled and terminating inwardly substantially flush with the inner face of said strip plate.

9. A pipe flask having an annular hub strip plate and a hub core plate detachably connected thereto in superposed relation, the hub core plate having formed thereon a sand core with a shodered base adapted to fit snugly in and be centered by the center opening of the strip plate and a marginal flange disposed to be engaged and held between said plates.

10. In combination, a pipe flask having annular strip plates mounted at its ends, hub and spigot pattern plates detachably engaging their respective strip plates and formed with pattern elements which interfit in the center openings of their respective strip plates and are centered thereby in the flask, and a body pattern adapted to be received in and centered by said pattern plates, a plurality of attaching elements, part of which attach only the strip plate to the flask and part of which attach the spigot pattern plate to the flask through the strip plate, whereby the pattern plates are demountable independently of the strip plates.

11. In a pipe flask, a cylindrical flask body externally threaded at its ends, a flange shaped to provide an annular seat secured to each body end with its seat flush with its respective end, a strip plate attached to each flange seat by elements having their heads countersunk in said strip plates, a hub core plate seated against the hub strip plate, and a spigot pattern plate seated against the spigot strip plate and bearing a spigot flange pattern which passes with a close centering fit through the center opening in said spigot strip plate, and handles on said spigot pattern plate for rotating it and holding it in place when serving as a strip plate for a pipe body pattern.

12. In a centrifugal sand lined pipe mold, an annular spigot strip plate and a superposed spigot plate having an annular flange fitted through the strip plate and provided at its inner end with an inwardly bevelled end chill face for the spigot flange of the pipe casting.

13. In an apparatus for the centrifugal casting of pipe in a sand lined mold, a flask comprising at its spigot end an annular strip plate mounted in position to define the spigot end of the sand mold and adapted to strip the spigot pattern used to form the spigot print, and a removable spigot plate mounted over said strip plate and having an annular shoulder fitted into the inner periphery of said strip plate and adapted to form a bevelled chill against which the spigot end of the pipe is cast.

14. A pipe flask having a hub flange formed with an annular countersunk seat, and an annular strip plate centered in and detachably connected to said seat, in combination with a hub pattern plate having a raised marginal shoulder loosely fitted in said seat and a pattern rigid thereon and centered in said seat only by engagement of the hub pattern base with the inner periphery of said annular strip plate.

15. In combination, a sand lined pipe flask adapted to be jolt rammed with its spigot end up and having annular strip plates mounted in centered relation at its ends, the spigot plate being apertured for the admission of sand to the flask, plates detachably engaging their respective strip plates and formed with pattern elements which interfit in the center openings of their respective strip plates and form the sole means for centering the pattern plates in the flask throughout the ramming operation, a body pattern adapted to be received in and centered by said pattern plates and, when drawn, to be stripped by said spigot pattern, and means to close the spigot strip plate openings during the pouring operation.

16. In a pipe flask, a cylindrical flask body having at each end a flange shaped to provide an annular seat, a strip plate attached in each flange seat by elements having their heads countersunk in said strip plates, a hub core plate mounted in and centered by the hub flange seat against the hub strip plate, and a spigot pattern plate mounted loosely in the spigot flange seat against the spigot strip plate and bearing a spigot flange pattern which passes with a close centering fit through the center opening in said spigot strip plate, and handles on said spigot pattern plate for rotating it and holding it in place when serving as a strip plate for a pipe body pattern.

HERBERT H. FARR.
